UNITED STATES PATENT OFFICE.

JAMES L. CAMPBELL, OF WEST ELIZABETH, PENNSYLVANIA.

THERMOSTAT.

SPECIFICATION forming part of Letters Patent No. 316,738, dated April 28, 1885.

Application filed June 23, 1884. (Model.)

To all whom it may concern:

Be it known that I, JAMES L. CAMPBELL, of West Elizabeth, in the county of Allegheny and State of Pennsylvania, have invented certain new and useful Improvements in Thermostats or Heat Regulators and Ventilators; and I do hereby declare the following to be a full, clear, and exact description of the invention, such as will enable others skilled in the art to which it pertains to make and use it, reference being had to the accompanying drawings, which form part of this specification.

My invention relates to an improvement in thermostats or heat regulators and ventilators to be used in connection with incubators, greenhouses, dwellings, churches, theaters, or any place where an even temperature is desired; and it consists, first, in the combination of the wooden bar with two straps of any suitable material, or wires which are applied to opposite sides thereof, and which straps or wires are provided with suitable means for increasing or decreasing their tension with the lever which extends a suitable distance upward, a clock mechanism for operating the revolving rod or lever, a valve which is placed in a suitable opening, a connecting-rod between the clock-work and the valve, and a connecting-rod between the clock-work and the upper end of the lever which is connected to the lamp-burner; second, in a valve which is placed in a suitable opening, and connecting both to the clock-work and to the lever which operates the lamp-burner, a revolving lever, and a lever which is connected with the thermostat; third, in the combination of the wooden bar, the two straps or wires which are applied to opposite sides thereof, a means for increasing or decreasing the tension of these parts, and a lever which is operated by one of the straps, all of which will be more fully described hereinafter.

The object of my invention is to place a valve in a suitable opening, and to so connect it with the thermostat and the clock-work mechanism that the slightest change or variation of temperature will cause the valve to open or close, as may be desired, and to turn on or shut off the heat at the same time, so that when the valve is opened for the purpose of lowering the temperature the heat will be turned off, and when the valve is closed for

the purpose of raising the temperature the heat will be turned on, and thus the temperature automatically regulated.

55

Figure 1 is a front elevation of a thermostat or heat-regulator embodying my invention complete. Fig. 2 is an end view of the same. Fig. 3 is a rear view. Fig. 4 is a plan view. Fig. 5 is a plan view of the wooden bar and its attachments. Figs. 6 and 7 are detail views.

My invention is here shown in connection with an incubator; but it is to be distinctly understood that it is applicable for regulating the heat wherever an even temperature is desirable.

A represents a rod of wood, which is suitably dried and prepared for use, in this connection by filling its pores with boiled linseed-oil, or by any other means that will render it water-proof and not easily affected by moisture. To opposite sides of this wooden bar are fastened the two straps B C. These straps may be made of either metal, rubber, or any other substance which is readily affected by changes of temperature, or metallic rods or wires can be used, if found more convenient than the straps. The strap B has both of its ends fastened rigidly to the wooden bar, as shown, or one end only may be fastened rigidly, and the other one provided with any suitable means for taking up any slack of the strap when it is expanded more than is desirable by the heat. A suitable bracket, D, is secured upon the top of the bar, and this bracket projects out over the top of the strap B and beyond the edge of the wooden bar any desired distance.

Through the end of the bracket D and through the strap is passed a suitable set-screw, E, which bears against the side of the wooden bar. When this screw is turned in one direction, the strap is forced outward from the side of the bar so as to tighten the strap, and in bearing against the wooden bar the bar is sprung slightly, and the effect of this upon the bar is to slightly shorten the bar upon the side upon which the set-screw is applied, and to lengthen the other side of the bar. When this screw is turned in the opposite direction, the tension of the strap and the wooden bar are both relaxed.

The strap C is secured rigidly at one end to

the wooden bar, and its other end is slotted where the screw F passes through it, and secured to this end of the strap is the screw F', which passes through the perforated plate G, which is secured to the end of the wooden bar. 5 Upon this screw is placed the nut H, by means of which the strap can be tightened. The screw F is not tightened in position until the strap has been sufficiently stretched by means of the 10 nut and its screw; but after a suitable tension has been applied to this strap the screw F is tightened in place so as to prevent any possibility of the strap slipping.

In the center of the wooden bar, just opposite 15 site where the set-screw E bears against it, is made a slot, opening, or recess, and in this recess is placed a suitable spiral spring, I, the outer end of which bears against the strap C for the purpose of forcing it away from the 20 side of the wooden bar. Attached to the outer side of this strap C, just opposite where the spring bears against it, is secured a small friction-roller, J, which bears against the disk upon the regulating-screw. 25

Secured to the under side of the wooden bar is a suitable bracket or support, K, the outer end of which extends a suitable distance beyond the side of the wooden bar, and in this outer end of the bracket is pivoted the lever 30 M. Through this lever M, or an arm or projection which is formed upon its side, is placed a regulating-screw, O, having the disk P upon its inner end. This disk P bears against the friction-roller and regulates the amount of 35 pressure which is to be applied by the strap to the lever. The friction-roller serves to decrease the friction against the disk as much as possible. When the regulating-screw is turned in one direction, a greater pressure is 40 brought to bear against the strap C, and when turned in the opposite direction the disk is moved away from the strap so as to decrease the pressure on the lever. It is not necessary that this lever should be pivoted to the bracket 45 and the regulating-screw used in the manner shown, for the lever can be pivoted directly to the strap C and the regulating-screw and its disk and the friction-wheel be dispensed with, and then the adjustment can be made by 50 the screw at the end of the strap.

The wooden bar does not expand or contract by the changes in temperature, but the two straps B C do. As their ends are both fastened so that they cannot move, the additional 55 lengths of the straps when expanded cause their central parts to move, and their motion is concentrated at their centers. When the strap B expands, the strain upon the wooden bar is relaxed, and the bar springs back into 60 the position it was before the set-screw was tightened. When the strap C expands, the coiled spring serves to force its central part away from the side of the bar, and this movement at this point is caught by the regulating-screw, which in turn communicates it to the lever. While the wooden bar is slightly sprung 65 by the pressure of the set-screw E the strap C

is tightened, and it is thus drawn closer to the side of the bar and against the pressure of the spiral spring and away from the regulating-screw. When the heat rises and the strap C expands, it becomes longer, and then the spiral spring forces it outward from the side of the bar and forces the friction-roller against the end of the regulating-screw. At the 70 same time that this strap C is lengthened by the heat, the strap B is lengthened, thus relaxing the pressure of the set-screw against the side of the wooden bar and allowing the bar to spring back into place. The 75 spring C being thus lengthened both by its own expansion and by the springing of the wooden bar back into place, it is forced farther from the side of the bar by the spiral spring than could be done if it had moved by 80 its own expansion alone. When the temperature falls, both straps are contracted and the wooden bar is drawn back into its sprung condition again. 85

When this thermostat is used in connection with an incubator, as here shown, the upper end of the lever M is passed up through an opening in the top of the incubator, and its upper end forms a support for one end of the revolving lever Q, which is operated by a 90 clock-work, R, of any suitable construction. This clock-work consists simply of a spring and a train of any suitable number of wheels, and this lever Q is connected to the shaft of the last one of the wheels or pinions, so 95 that when the wheels revolve this lever will be made to sweep around through a circle. One arm of this lever is longer than the other, and one arm will always bear upon the top of the lever M. When the short arm of 100 the lever Q rests upon the top of the lever M, it rests upon the side of the lever M which is next to the bar. When the expansion of the straps causes the lever M to be forced back, the upper end of the lever M slips from under the short arm of the revolving lever Q. When the lever Q makes a half-turn, its longest arm catches on the opposite side of the upper end of the lever M, or that side which is farthest from the bar. When the fall of temperature causes the lever M to move inward, its 105 upper end slips from under the long arm of the lever Q, the lever Q makes a half-turn, and its short arm catches on that side of the upper end of the lever M which is nearest to the bar. 110

Bearing against the outer side of the lever M is a suitable spring, R', which causes the lever to move inward as soon as the straps begin to contract. The lever being forced in one direction by this spring R' and in the other direction by the expansion of the straps, has its upper end moved back and forth by every change of temperature. When the change of temperature becomes sufficiently marked, the movement of the upper end of this lever causes the revolving lever to make one-half of a revolution, and thus reverse its ends. The shaft S extends through on both sides of the move- 115 120 125 130 135

ment and has the crank T attached to its rear end. To the wrist of this crank is attached the connecting-rod U, which rod U has its other end attached to the crank V of the valve 5 W. Also attached to this crank is the connecting-rod X, which has its outer end attached to the upper end of the lever Y, which is pivoted upon one end of the frame, and is connected at its lower end by the connecting- 10 rod Z with the lamp-burner or other source of heat.

Through the top of the incubator, in the transom or opening which is made in the greenhouse or dwelling, is pivoted the valve 15 W, which when open allows the heated air to escape, and which when closed prevents the escape of the heated air, so that the temperature in the incubator, house, or dwelling will rise. As this valve W and the lamp-burner 20 or other source of heat are both connected to the same crank, it will readily be seen that when the valve W opens the upper end of the lever, which controls the heat, is drawn inward so as to turn down the lamp-burner or shut 25 the source of heat off, and when the damper is closed the upper end of the lever Y is forced in the opposite direction for the purpose of turning on the heat for again raising the temperature. These parts being thus operated by 30 the same crank, when the valve is opened the heat is shut off, and when the valve is closed the heat is turned on.

When the short end of the lever Q is resting upon the top of the lever M, the valve is closed, 35 and when the long end of the lever Q is resting on the upper end of the lever M the valve is open and the source of heat shut off. As the lever Q makes only one-half of a revolution at a time, the crank on the other end of 40 the shaft is turned just far enough to cause the valve W to open or close and at the same time move the upper end of the lever Y just far enough to operate the burner or other source of heat.

45 The lamp-burner a is of any ordinary construction, and pivoted upon its top are the two leaves or reducers A', which are made to close against opposite sides of the wick when the heat is to be shut off, so as to turn down the 50 flame to the lowest possible point. Each of these leaves or reducers is attached to a wire which is pivoted in the burner. The wire B' has a weight, C', connected to it at one end for the purpose of throwing the leaves or reducers 55 outward from the wick when left free to move, and has the crank or bend D' upon its other end for the purpose of catching over a corresponding crank or bend, E', upon the other wire, F'. The opposite end of the wire F' 60 from the cranked one is formed into a loop, or catch, G', which is connected to the connecting-rod Z. These two wires, having their ends bent so as to engage with each other, are caused to move alike, and thus move the leaves away 65 from the wick or against it at the same time. When the lower end of the regulating-lever Y

is forced inward by the movement of the crank at the outer end, the weight C' causes both leaves to instantly spring backward from the side of the wick, and thus allow a full blaze at 70 once.

The lamp-burner just described is used in connection with an incubator; but where my invention is applied to hot-houses, churches, theaters, or dwellings the lower end of the lever Y will be connected by the rod Z with some other means of controlling the heat—such as a damper to cut off the draft.

In case it should be desired to dispense with the clock-work and the revolving lever, the 80 upper end of the lever M, which is connected to the thermostat, may be connected by a connecting-rod with the upper end of the lever Y, and the movement of the lever M thus made to control the heat.

Having thus described my invention, I claim—

1. In a heat-regulator, the combination of the wooden bar with two straps, rods, or wires attached to opposite sides thereof, with the lever which is operated by the expansion and contraction of the straps, substantially as shown.

2. In a thermostat, the combination of the wooden rod with the two straps, wires, or rods attached to opposite sides thereof, the set-screw for springing the rod upon one side, and the lever which is operated by the movement of the strap, spring, or rod upon the other side of the wooden bar, substantially as described.

3. The combination, in a thermostat, of the wooden bar, the two straps, wires, or rods attached to opposite sides thereof, a set-screw for springing the wooden bar upon one side, and a suitable spring which is placed between the wooden bar and the strap upon the opposite side of the bar from the set-screw, and a lever which is operated by the movement of the strap which has the spring applied thereto, substantially as set forth.

4. In a thermostat, the combination of the wooden bar, the two straps, wires, or rods attached to opposite edges thereof, one of the straps being provided with a screw and nut for regulating the tension of the strap, substantially as specified.

5. The combination, in a thermostat, of the wooden bar, the two straps, wires, or rods attached to opposite sides thereof, a set-screw for springing the wooden bar, a coiled spring which is placed between the side of the bar 120 and the inner side of one of the straps, the pivoted lever, a revolving lever, and a mechanism for moving the revolving lever, operating the valve, and shutting off and turning on the heat, substantially as shown.

6. The combination of the wooden rod or bar, the straps, wires, or rods attached to opposite sides thereof, a set-screw for springing the bar upon one of its sides, a coiled spring, a pivoted lever, and a regulating-screw, which 130 is connected to the lever, a spring for bearing against the lever upon one side, a revolving

lever, and the clock-work for operating the valve and turning on or shutting off the heat, substantially as described.

7. In a thermostat, the combination of the lever which is moved at its lower end by the expansion and contraction of a metallic strap, rod, or wire, a spring for bearing against the side of the lever and forcing it toward the strap, wire, or rod, a revolving lever, a mechanism for revolving the lever, a valve which is placed in a suitable opening, and a mechanism which is attached to the source of heat, substantially as set forth.

8. The combination of a lever which is moved at its lower end by the expansion and contraction of a strap, rod, or wire, a spring for bearing against the side of the lever, a revolving lever having arms of different lengths, a mechanism for revolving this lever, and which is provided with a crank, a valve which is connected to the crank, and a lever which controls the heat, the valve and the lever being operated at the same time, substantially as specified.

25 9. The combination of a thermostat substantially as shown, a lever which is connected thereto, a revolving lever having arms of different lengths, a mechanism for revolving

the lever and which is provided with a crank, and connecting-rods which are attached to this 30 crank and extending in opposite directions, a valve provided with a crank, and a lever which turns on and shuts off the heat, substantially as shown.

10. The combination of the thermostat and 35 a vertical lever which is connected to and operated thereby, and which has its upper end to project through an opening in the top of the frame, with the pivoted lever Y, for operating the flame, and a suitable connection between 40 the ends of the two levers, whereby the movement of one controls the movement of the other, substantially as set forth.

11. The combination of a thermostat, a pivoted lever, Y, and a lamp-burner provided 45 with two leaves or reducers, suitable pivotal wires which are connected together, one of which is provided with a counter-weight, substantially as set forth.

In testimony whereof I affix my signature in 50 presence of two witnesses.
